UNITED STATES PATENT OFFICE.

WILLIAM J. NEWTON, OF LYNBROOK, NEW YORK, ASSIGNOR TO METROPOLITAN ELECTRIC MFG. CO., A CORPORATION OF NEW JERSEY.

SWITCH.

1,094,806.

Specification of Letters Patent. Patented Apr. 28, 1914.

Application filed November 15, 1912. Serial No. 731,520.

To all whom it may concern:

Be it known that I, WILLIAM J. NEWTON, a citizen of the United States, residing at Lynbrook, in the county of Nassau and 5 State of New York, have invented certain new and useful Improvements in Switches, of which the following is a full, clear, and exact description.

This invention relates to that class of 10 electrical appliances in which contact terminals are housed or located within a casing or receptacle and a circuit is completed by introducing into said casing or receptacle a member, which may be called a plug, 15 carrying corresponding terminals which thereby engage the terminals in the casing. A familiar form of such an appliance is known in the art as a plug switch. Devices of this character are subject to the 20 disadvantage that while the contacts in the receptacle portion are to a considerable extent protected by the casing and the face-plate, they are nevertheless so placed as to be accessible to malicious, careless or heedless persons, who by inserting a foreign 25 conducting body into the casing may short circuit the contacts therein and in the case of a child who may thrust its finger into the receptacle a severe shock may be experienced. Furthermore, in the operation 30 of these devices, the plug which is operated by hand is oftentimes pushed into or pulled out of the receptacle slowly or in a hesitating manner, which causes an arc to form 35 between the contacts of the receptacle and those of the plug, which arc is often a cause of serious fires.

The object of the present invention is to 40 so construct a device of this kind that the exposed contacts in the receptacle portion will not be "alive" or receive current until the plug portion has entered the receptacle and made fair and full contact with the 45 contacts therein, and will become "dead" or devoid of current before the plug has been entirely removed from connection with the receptacle contacts. In such a device no arc can form either upon the entry or 50 withdrawal of the plug and the contacts of the receptacle will when not in use be dead.

My invention likewise has other objects 55 of minor importance such as a cheap, compact and simple construction which is efficient and sure in its operation.

To these ends my invention consists broadly of a switching device of the character above referred to in combination with an electric switch adapted to open and close by reason of the relative movements of the 60 two parts of the switching device.

More specifically, my invention consists of the combination of a plug switch and another switch adapted to be closed and opened by the insertion and removal of the 65 plug and controlling the flow of current to the contacts of the plug switch.

The invention further consists of certain combinations and constructions hereinafter described and pointed out in the claims. 70

Referring now to the accompanying drawings wherein is shown one of the various possible embodiments of my invention, Figure 1 represents a partial longitudinal sectional elevation taken approximately on the median line of the device showing the face-plate in position; Fig. 2 represents a longitudinal sectional elevation taken substantially on the median line of the receptacle and showing the plug 80 member in place with a part broken away; Fig. 3 represents a plan view of the receptacle with the face-plate removed; and Fig. 4 represents a side sectional elevation of the device taken on the line $x-x$ of 85 Fig. 2.

Similar reference numerals refer to similar parts in the various views of the drawings.

Referring now to the drawings in detail, there is shown a form of plug switch which is substantially the same as that set forth in my previous application, Serial No. 643,708, filed August 12, 1911. Only those features of the previous construction, which are important in connection with the present invention will, therefore, now be described. The plug switch includes a receptacle, which comprises a base or body portion 1 composed of rubber or other form of insulating material. The base portion is provided with a substantially rectangular interior chamber and has the customary opening adapted to be covered by a face-plate 2. This face-plate is provided with inwardly swinging doors 3 through which the contact or plug member 4 (as shown in Figs. 2 and 4) is adapted to pass.

Current is adapted to be led into the receptacle through the binding screws 5, as

shown more clearly in Fig. 3, which are disposed adjacent the opening of the receptacle at diagonally opposite corners. The binding-screws pass through the over-turned extremities 6 of conductors which extend along the inner wall of the receptacle toward the rear wall thereof. At or near the middle part of the upright portion 7 of each of these conductors is a bracket 8 which extends outwardly therefrom in a plane substantially parallel to the adjacent side wall of the receptacle. Supported by the brackets 8 is a two-pole switch, and since each of the blades 9, 9 of this switch and its associated parts are substantially the same, it is believed that a description of one will suffice for the other. This two-pole switch is adapted to quickly make and break and thereby control the circuit to the contacts in the receptacle by a construction hereinafter set forth.

The blade 9 is pivotally attached near its extremity to the bracket 8 at or near the extremity of the latter, the pivot pin 10 projecting through the blade and bracket. At a point between the pivotal point just mentioned and the adjacent extremity of the blade 9, is pivotally attached a lever 11 which, with its associated parts, is adapted to provide a snap-switch action to the blade 9. This lever 11 is provided with a stirrup-shaped member 12 at one extremity thereof and the stirrup embraces the adjacent end of the blade 9. Through the stirrup and the extremity of the blade passes a pin 13 serving to pivot the parts together. The end of the lever 11 opposite the stirrup member passes through an aperture in swivel block 14 which is pivotally attached to the adjacent bracket by the pin 15. The lever 11 is adapted to reciprocate through the aperture in the swivel block when the blade 9 moves. Between the swivel block and the stirrup member and coiled about the lever is a helical spring 15'. A V-shaped plate 16 is also pivoted near its vertex about the pin 10 and is provided with a laterally-projecting lug 17 and a second shorter laterally projecting lug 18, the lugs being on the opposite diverging sides of the plate remote from the vertex. These two lugs serve to contact with opposite edges of the blade 9 at points adjacent the center thereof, for a purpose which will be hereinafter more specifically pointed out. The V-shaped plate is provided with an apertured tail-piece 19, through the aperture of which passes one end of a spring member 20 the opposite end of which is connected to the conductor-foot 21 which extends outwardly along the bottom wall of the receptacle from the body portion 7 of the conductor, through which current for the device passes. The end of the blade 9 opposite the pivoted end springs freely and is limited in its upward motion

by means of a pin 22 which is attached to the side wall of the receptacle.

As described in my previous application, the receptacle comprises a projecting boss 23 disposed on the inner rear wall thereof, on either side of which boss are arranged the upwardly-projecting terminals 24 of a second set of conductors 25 which are attached to the rear wall of the receptacle by screws. These conductors are provided with integral branches 26 which extend into diagonally opposite corners. To these branches are attached resilient jaws 27 of copper or other material which are adapted to receive, respectively, the free ends of the blades 9 when these have been swung downwardly into engagement therewith.

The plug 4 is provided with a hollow portion 28 which is provided with contacts 29 on the interior thereof adapted to contact with the terminals 24 as heretofore described in connection with my other application.

In operating the present device, the plug is forced into the receptacle through the doors 3 and after it has advanced well over the boss 23 and made good contact with the terminals 24, the lower edges engage with the laterally-projecting lugs 17, having passed the lugs 18, which are shorter. And upon further movement into the interior of the receptacle, these lugs 17 are forced downwardly against the action of the spring 20 until the lugs 18 come in contact with the blades 9. Thereupon the blade begins to move downwardly at a rate dependent upon the inward motion of the plug, but when the blade has swung the pivoted lever 11 about the pin 15 until the pivot pins 10, 13 and 15 are just beyond alignment, the snap switch action of these parts will come into play and will snap the blade 9 rapidly into contact with the jaw 27. Current will thereupon flow through a circuit from binding screw 5 through blade 9, jaw 27, conductors 26, 25 and 24, and the circuit will be completed by passage through the similar set of conductors to the diagonally opposite binding-post. The two-pole switch is then included in this circuit in the receptacle and upon movement therein is adapted to make and break this circuit. The general action of the snap switch is of course well known and in this instance is brought about by the compression of the spring 15' between the stirrup member and the base block. This spring action, acting through the pivot pin 13, throws the blade 9 rapidly about the pivot pin 10 when the parts have been brought slightly out of alignment, as heretofore mentioned. But it will be seen that the switch is not closed until the plug is in fair contact with the receptacle terminals, so that the slow initial movement of the plug into engagement with the terminals 24 cannot cause an arc to form between them and

the plug, because terminals 24 do not receive current until the plug has entered into good contact therewith.

Upon retraction of the plug, the action of the parts is substantially reversed, the V-shaped plate being gradually raised by the spring 20 until the lug 17 contacts with the blades 9, thereby raising the blades 9. Upon this reverse movement of the blades the springs 15' are again compressed and when the point of alinement of the pivot pins is slightly exceeded, the springs provide the snap switch action for the reverse direction. This action takes place before the contacts of the plug have severed their connection with contacts 24, so that at the instant this separation takes place the contacts 24 are "dead" and no arc can form.

It will be noted in connection with the device that the blades 9 are pivoted at opposite ends so that the free ends swing in opposite directions and the jaws which coact with the blades are located consequently in diagonally opposite corners. By thus removing the contact members to points as remote from each other as possible in the receptacle and out of alinement with the opening in the face-plate, the chance for short-circuiting by the insertion of an instrument is substantially overcome. In connection with the V-shaped plate and the lugs attached, it will be noted that by providing the longer lugs on that side of the plate which is remote from the face-plate, the plug may travel into the receptacle a much longer distance than would be possible if the lug 18 were the longer and contacted with the lower edges of the plug. It will

thus be seen that the invention admirably achieves the objects sought. 40

As many apparently widely different embodiments of this invention might be made without departing from the scope thereof, it is intended that all matter contained therein shall be interpreted as illustrative 45 and not in a limiting sense.

Having thus described my invention, I claim:—

1. In combination, a receptacle provided with a pair of interior contacts, a hollow 50 plug containing on its interior a pair of contacts corresponding to those in the receptacle, and an electric switch located within the receptacle and having its movable member in the path of travel of the wall of said 55 plug whereby the plug is adapted to actuate the switch.

2. A receptacle provided with a rectangular internal lug projecting from its bottom, two contacts located against opposite faces 60 of said lug, two mechanically independent electric switch levers mounted in said receptacle and controlling the circuit to said contacts, in combination with a plug having a rectangular orifice therein adapted to fit 65 over said lug, said plug having two internal contacts adapted to engage with the contacts in the receptacle, and said switch levers being located in the path of travel of the wall of said plug. 70

In witness whereof, I subscribe my signature, in the presence of two witnesses.

WILLIAM J. NEWTON.
